UNITED STATES PATENT OFFICE.

McCLINTOCK YOUNG, OF FREDERICK, MARYLAND.

BRUSH-MACHINE.

SPECIFICATION forming part of Letters Patent No. 423,507, dated March 18, 1890.

Application filed May 21, 1889. Serial No. 311,571. (No model.)

To all whom it may concern:

Be it known that I, MCCLINTOCK YOUNG, of Frederick, in the county of Frederick and State of Maryland, have invented certain Improvements in Brush-Machines, of which the following is a specification.

This invention relates to a machine intended to facilitate the separation of bristles into tufts, the folding or doubling of these tufts, and finally their insertion into holes or seats in the brush-block.

In the accompanying drawings, Figure 1 is a front elevation of a machine containing my improvements. Fig. 2 is a perspective view of the bristle-support. Fig. 1^a is a horizontal cross-section through the bristle-dividing inserting-blades. Fig. 3 is a side elevation of the machine. Figs. 4, 5, and 6 are cross-sections on the line x x, Fig. 1, showing the successive steps in the formation and introduction of the tufts. Fig. 7 is a side view, partly in section, showing the manner in which the layer of bristles is divided into tufts. Fig. 8 is a similar view showing the manner in which the tufts are carried downward between the dividing-teeth into the block.

Referring to the drawings, A represents a rigid frame or standard mounted on legs or otherwise suitably supported.

B represents a table or bed fixed to the side of the frame and grooved longitudinally in its upper face to receive the brush-block C, and admit of the same being moved endwise, by hand or otherwise, step by step, in order to bring the successive rows of tuft-holes beneath the inserting devices. The table may be secured rigidly to the frame or pivoted thereto, as shown, in order to admit of its inclination being changed when tufts are to be inserted into inclined holes. The manner of attaching this table forms no part of the present invention.

D represents a fixed bristle-support bolted to the frame. It is in the form of a horizontal plate, one end of which is extended to the right and turned upward in order to receive and hold a supply of bristles, while the other end is extended horizontally over the position occupied by the brush-block. The end which overlies the brush-block is provided with a vertical slot d, extending in a direction transverse to the block. It is also provided with

a horizontal finger d', lying slightly above and parallel with the surface of the plate and sustained wholly at the upper or elevated end, 55 so that the bristles may be passed thereunder from the right in such manner as to lie across the slot d in a sheet or layer. A gage bar or guide d² extends along the rear edge of the plate, and is secured by bolts d³, passing 60 through slots, so that it may be adjusted forward and backward. The bristles are cut to a uniform length and presented at the rear end against the gage which serves to control their longitudinal adjustment, so that they 65 will always extend equal distances on opposite sides of the slot.

The inserting devices are located directly above the support D. They consist, essentially, of two vertically and independently 70 movable blades E and F, each provided with a series of downwardly-extending teeth at the lower end. The teeth of the blade E are pointed to pass through the layer of bristles upon the plate D and divide the same into 75 bunches or tufts, as shown in Figs. 4 and 7. The blade F has its teeth notched or indented at the end and located opposite the spaces between the teeth of blade E. After the layer of bristles has been divided by blade E into 80 tufts or bunches the blade F descends, and its notched teeth act upon the tufts midway of their length, driving them down through the slot d. The tufts are by this action doubled or folded over the teeth, which continue their 85 descent until they carry the tufts deeply to their places in the holes of the brush-block, as shown in Fig. 6.

The dividing-blade E descends only until its teeth rest upon the upper surface of the brush-block between the tuft-holes, as shown in Figs. 6 and 8, when it remains at rest, so that its fingers serve thereafter as vertical guides to assist in confining and directing the tufts as they are carried downward between 90 them by the teeth of the inserting-blade.

This machine is intended only to seat the tufts in place. They may be secured thereafter by transverse wires, applied as shown in my application, Serial No. 280,502, dated 100 July 20, 1888, or in any other suitable manner.

The dividing and inserting blades E and F may be mounted and operated in any appropriate manner; but I recommend for this pur-

pose the arrangement represented in the drawings, in which the driving-blade F is secured rigidly to a vertical slide G, mounted in guides in the main frame and connected by a link g to crank-arms g' on a horizontal rock-shaft g², this shaft being mounted in bearings g³ in the frame and provided at one end with a hand-lever g⁴. The plate E is mounted to slide vertically in suitable guides on the face of the blade F, as shown in Fig. 1^a, and connected by a link e to one end of a lever e', which is pivoted at the middle to the blade F or its carrying-slide, and arranged at the opposite end to encounter a stationary stop e² when the parts are elevated. A spring e³ urges the blade E constantly downward in relation to the blade F. When the parts are in their normal elevated position the blade F stands above the blade E, as shown. When the slide G is lowered by the hand-lever, the lever e' is carried away from the stop and the spring e³ permitted to drive the fingers of the blade F downward through the layer of bristles and downward through the slot in the supporting-plate until the ends of the teeth rest upon the face of the block. The blade F, following downward, acts within the tufts and, overcoming the blade E, passes beyond the same, forcing the tufts to their seats.

30 The essence of my invention resides in the combination of two toothed blades—one adapted to divide the bristles into tufts and the other to force these tufts into the block.

As regards the support D the only requirement is, that it shall be adapted to sustain the bristles in a sheet or layer, and that it shall have a slot or opening through which the blade may pass, and by which the bristles shall be divided or folded over the ends of the blades.

I do not claim herein the dividing-blade E or the separation of these blades broadly with a slotted support for the bristles. Neither do I claim herein the special arrangement of devices for imparting the differential motion to two blades, the same being the subject-matter of a separate application, Serial No. 311,572, filed May 21, 1889.

Neither do I claim herein the table pivoted to the frame, as herein shown, the same being also claimed in the above-mentioned application.

While I have represented herein a sta-

tionary support for the bristles, it is to be distinctly understood that the two toothed blades herein shown may be used in combination with any suitable automatic mechanism for feeding the tufts of bristles.

Having thus described my invention, what I claim is—

1. In a machine for forming and inserting tufts, the combination of a slotted bristle-support, a blade movable through said slot and provided with teeth to divide the bristles into tufts, and a second blade also movable through the slot to drive the tufts to their seats in the brush-block.

2. In a brush-making machine, the brush-block support, the slotted bristle-support thereover, and the two independently-moving blades, one provided with teeth to separate and guide the bristles and the other provided with teeth to carry the bristles into the block.

3. In a brush-machine, and in combination with an underlying support for the brush-block and an inserting device which acts from above, a slotted bristle-support provided with a fixed overlying finger d' to confine the bristles in position.

4. In a brush-machine, the bristle-support consisting of the plate provided with the upturned end, the vertical slot at the opposite end, and the overhanging finger d' to confine the bristles in position across the slot.

5. In a brush-machine, in combination with a bristle-support having an opening through which the bristles may be folded and delivered, a reciprocating blade having teeth to divide the bristles and an independently-movable reciprocating blade having tuft-driving teeth intermediate of the teeth of the first-named blade.

6. In a brush-making machine, in combination with a suitable bristle support, a reciprocating blade with pointed teeth to divide and unite the bristles, and a second and independently-movable blade with tuft-driving teeth, the ends of which are indented to straddle the tufts within their bight or fold.

In testimony whereof I hereunto set my hand, this 10th day of May, 1889, in the presence of two attesting witnesses.

MCCLINTOCK YOUNG.
